BATTERY SHIELD

Morris F. Glycer, Sacramento, Calif., assignor to
R. E. Dietz Company, Syracuse, N.Y.

Application April 11, 1958, Serial No. 50,441

Term of patent 14 years

(Cl. D26—6)

Fig. 1 is a top plan view of a battery shield, showing my new design;

Fig. 2 is a side elevational view, the opposite side being substantially a mirror image thereof; and

Fig. 3 is a cross-sectional view thereof, taken on line 3—3 in Fig. 1.

A portion of the drawing figures is diagonally lined to indicate transparency.

I claim:

The ornamental design for a battery shield, as shown and described.
